(57) **CLAIM**

The ornamental design for a “presentation board,” as shown and described.

DESCRIPTION

FIG. 1 is a perspective view of a presentation board, showing our new design;

FIG. 2 is front plan view of a presentation board shown in FIG. 1;

FIG. 3 is a back plan view of the presentation board shown in FIG. 1;

FIG. 4 is a top elevational view of the presentation board shown in FIG. 1;

FIG. 5 is a bottom side elevational view of the presentation board shown in FIG. 1;

FIG. 6 is a left side elevational view of the presentation board shown in FIG. 1;

FIG. 7 is a right elevational view of the presentation board shown in FIG. 1;

FIG. 8 is a left side exploded elevational view of the presentation board shown in FIG. 1;

FIG. 9 is a right side exploded elevational view of the presentation board shown in FIG. 1;

FIG. 10 is an exploded front and right side perspective view of a presentation board of the presentation board shown in FIG. 1; and,

FIG. 11 is an exploded front and left side perspective view of a presentation board of the presentation board shown in FIG. 1.

The broken lines in the drawings illustrate unclaimed portions of the presentation board and form no part of the claimed design.
